UNITED STATES PATENT OFFICE.

NATHAN F. BURNHAM, OF YORK, PENNSYLVANIA.

STEAM-ENGINE.

SPECIFICATION forming part of Letters Patent No. 336,837, dated February 23, 1886.

Application filed October 7, 1885. Serial No. 179,251. (No model.)

To all whom it may concern:

Be it known that I, NATHAN F. BURNHAM, a citizen of the United States, residing in the borough of York, in the county of York and State of Pennsylvania, have made certain new and useful Improvements in Steam-Engines, of which the following is a specification.

My invention more especially relates to that class of engines having a double-acting cylinder provided with an automatic cut-off.

Its objects are to provide a cheap, simple, durable, and effective automatic cut-off engine capable of running at a predetermined high rate of speed, to maintain that speed by means of a self-regulating governor, to provide a continuous, effective, and automatic lubrication, and to prevent the escape and waste of the lubricating materials.

The accompanying drawings represent all of my improvements as embodied in a single vertical cylinder-engine. I may, however, mount two cylinders in one frame and have them act upon a single shaft. Obviously, however, the details of the invention may be varied, and some of the improvements may be used without the others, and in machines differing somewhat in their details of construction, without departing from the principle of my invention.

Figure 1 represents a perspective view of my improved engine inclosed in its casing. Fig. 2 represents a view partly in elevation and partly in vertical longitudinal central section through the engine. Fig. 3 represents a vertical transverse section through the steam and slide cylinders and their appurtenances on the line 3 3 of Fig. 2. Fig. 4 represents an end view, partly in section, on the line 4 4 of Fig. 2, showing the details of the automatic governor. Fig. 5 is a detail view showing the plate that carries the valve-rod eccentric; Fig. 5^a, a view of the eccentric for operating the valve-rod removed from its plate and showing its inner face; Fig. 6, a detail plan view, with the piston-rod in section, of the cross-head or slide, with the guide in which it works shown in section; Fig. 7, a detail view, partly in section, showing the cross-head or slide-head; Fig. 8, a plan view of the under side of the slide-head; Fig. 9, a detail elevation of the slide-head at right angles to the view shown

in Fig. 7; and Fig. 10 is a detail view of a slight modification of one of the details of construction.

The frame of the engine is shown as composed of four standards or posts, A A' A² A³, strongly bolted to or cast in one piece with a base, B, which may be firmly secured to a suitable foundation. A bowl-shaped basin, B', formed in the base, constitutes a receptacle for oil and waste condensed steam should such there be. The tops of the frame-pieces A A' A² A³ are planed smooth to fit correspondingly-prepared surfaces on the under side of a cap-plate, C, to which they are securely bolted. The steam-cylinder D is provided with an annular flange, d' d², at each end, accurately turned to fit its contiguous surface. The upper flange, d², of the cylinder fits over a slight boss or projection, c, on the under side of the cap C, and is bolted to the cap.

A transverse diaphragm or cylinder-head, D, is interposed between the lower flange, d', of the cylinder and the flange or flanges f of a guide, F, forming a prolongation of a steam-cylinder in which the slide-head of the piston works. This guide is preferably of the general form of a longitudinally-slotted cylinder, and in Figs. 3, 4, 6, and 7, F represents side portions of the cylinder, between which the slide-head works. The piston-rod e of the steam-piston E passes through a stuffing-box, E', in the cylinder-head D, and is attached at its lower end to the slide or cross-head G, traveling in the guide or slotted cylinder F. The slide-head has two downwardly-projecting lugs or ears, g, which carry the pivot-pin h, with which the connecting-rod H is attached, Figs. 7 and 8. The connecting-rod at its lower end is connected to the crank-shaft I, which turns in suitable boxes or bearings, J, in the frame. The slotted guide-cylinder F affords an ample bearing for the slide-head G, and at the same time permits a free circulation of air, which prevents undue heating. The slots are preferably extended nearly the whole length of the cylinder, leaving merely a solid ring or section at each end.

M is the ordinary exhaust-steam chest. The valve cylinder or chest L is cast with the steam-cylinder, or may be separate and

bolted to the side of the cylinder, and is connected therewith by the usual ports, M' M'. Steam enters by the pipe L' and inlet L''.

5 m' indicate the open ends of the valve-cylinder, through which exhaust-steam passes to the escape-pipe K.

In order to secure an equal steam-opening around the heads of the valve-cylinder, I form the cylinder with sharp edges x at the ports.

10 These lips are, in the manufacture of the engine, formed somewhat longer than necessary, and are then turned or ground down, so as to insure an absolutely accurate cut-off and admission of steam.

15 The valve-piston consists of two accurately-turned heads, which closely fit the valve-cylinder, and are united by a neck, N, of smaller diameter, thus forming a chamber or passage between the heads of the piston for the admission of steam to the cylinder. The heads of the valve-piston may be turned solid or provided, as preferred, with packing-rings of well-known construction.

20 The valve-stem M² works through a stuffing-box or gland, M³, and is connected by a pivot-pin, o, and connecting-rod O with the yoke P, which encircles the actuating-eccentric Q, driven by the main crank-shaft I.

The gravity of the valve-piston stem and 25 connecting-rod may be counterbalanced by a spring interposed between the lower piston-head and the bottom of the valve-chest, as shown in Fig. 2. The valve will therefore work with equal ease in either direction, a great 30 advantage in engines designed for high speed, or a spring to accomplish the same purpose may be placed at the top of the valve-piston, as shown in Fig. 10.

The eccentric Q, which actuates the valve-35 spindle, is made adjustable to regulate the relation of the valve-cylinder to the steam-ports, or, in other words, the lap and lead of the engine, as presently described. Its position is also controlled by an automatic governor.

40 As seen in Fig. 5^a, it is formed with an elongated opening or slot, q, through which the main shaft I loosely passes. This gives the eccentric a capacity of being moved laterally relatively to the shaft to change the position 45 of the bulge of the eccentric relatively to the center of motion, and correspondingly vary the relation of the valve-piston to the steam-ports, as is well understood.

The eccentric Q is carried by a plate, S, having 50 an elongated opening, like that q in the eccentric, through which the main shaft I also passes, as seen in Fig. 5, and is made with a groove, q', formed in the arc of a circle, Fig. 5^a, which fits over a correspondingly-curved

55 rib or boss, q², on the movable plate S. The eccentric and plate S are bolted together by bolts R R', which pass through elongated openings r r' in the eccentric. The eccentric may therefore be rotated within limits with reference to the plate S, to adjust it to the proper 60 position to give the desired lap and lead, and

may then be firmly bolted in place. The plate S is movably carried by a frame or flanged disk, T, which is fast on the main axle I through the medium of the governing devices, which I will now describe.

The plate S is provided at each end with a boss, s s', which passes through an elongated opening, t t', in the frame or disk T. Each of said bosses is pivotally connected with a governor-lever, U U', by a bolt, R³ R', as shown in Figs. 2 and 4. These governor-levers are respectively pivoted on the disk T on opposite sides of the main shaft by bolts T³ T', preferably in the same horizontal plane, as shown. 75 The outer ends of the levers are made larger and heavier than the inner ends, as illustrated, and are curved in the arc of a circle, so as to rest upon a boss or hub, either formed with the disk T or separately keyed to the main shaft, 80 or they might bear directly against the main shaft.

85 Plate-springs u u' are adjustably secured at one end upon the flange of the disk or frame T, and at their outer ends carry rollers u² u', 90 which bear upon the governor-levers U U' and tend constantly to press them toward the main shaft, or, in other words, to overcome their centrifugal tendency. The springs are secured by bolts to thickened concaved portions of the 95 flange of the disk T, as shown in Fig. 4, and by screwing the bolts up more or less the free ends of the springs carrying the rollers may be caused to press with more or less power upon the outer edges of the weighted governor-levers. The springs may of course, if desired, 100 be provided with elongated slots, through which the securing-bolts pass, and be adjusted endwise to vary their pressure upon the governor-levers. An accelerated motion of the 105 engine and main shaft will cause the governor-levers, in obedience to centrifugal force, to swing out from the shaft I, and, turning upon their pivots T³ T', will in conjunction move the plate S, which carries the eccentric transversely to the main shaft. This varies the 110 relation of the eccentric to the center of motion, and correspondingly controls the relation of the valve-piston to the steam-ports. The engine is therefore perfectly and automatically 115 controlled.

120 Of course it will be observed from the drawings that one of the weighted governor-levers is pivoted to the boss on the plate S between the pivot of the lever and its free end, while the other governor-lever is pivoted to its boss on the opposite end of the plate S by means of a prolongation of the lever beyond its pivot. They both therefore tend to move the plate S in the same direction.

125 In the drawings the parts are shown in the position they occupy when the engine is at rest.

In this application no claims are made to the specific construction of the governor, as such subject-matter is covered by another application filed simultaneously herewith. The 130

automatic governing devices have, however, been described in detail, so that their action in relation to the other parts of the engine will be fully understood.

5 I automatically effect the perfect lubrication of the engine by certain improved arrangements which I will now describe. Such subject-matter is not, however, specifically claimed herein, as it is covered by another 10 application filed by me simultaneously herewith.

The slide-head and its bearing in the slotted guide F are lubricated by oil flowing from a tank, V, through a pipe, v, which terminates 15 immediately over an aperture, h', in a plate on top of the slide-head G. The tube v contains a wick, which permits the slow feeding drop by drop of the oil from the tank V into a chamber, v', on the top of the slide-head. 20 This chamber is formed by vertical flanges on the top of the slide-head and the cover-plate v', and is filled with wool, cotton-waste, or other suitable fibrous material, which becomes saturated and feeds the oil slowly through 25 apertures v'. These apertures communicate with oiling-grooves v⁶, formed in the outside of the downwardly-projecting lugs g, Figs. 7 and 9, so as to distribute the oil over the bearing in the guide. A tube, v⁴, leading from this chamber and containing a suitable wick, projects 30 from the under side of the slide-head between the lugs g, as shown in Fig. 3. The end of the wick projecting from the tube v⁴ is so placed with relation to a tube, v⁵, having a cup-shaped mouth and leading to the bearing of 35 the connecting-rod in the slide-head, that as the connecting-rod oscillates the projecting end of the wick will be struck by the mouth of the tube v⁵, and the oil fed drop by drop 40 to the bearing. The crank or eccentric connection of the connecting-rod with the main shaft is lubricated in a similar manner by oil flowing from a reservoir, W, through a pipe, w, filled with wicking, the lower end of which 45 projects beyond the end of the pipe. The sharp-edged cup-shaped mouth of the tube w', carried by the connecting rod or crank, shaves past this wick on each revolution of the crank, thus feeding the oil little by little to the bearing. 50 The journals of the main shaft I are lubricated by oil from the tanks J, Fig. 2. The oil is prevented from passing endwise along the crank-shaft to the outside of the casting by sharp-edged rings X, secured to the 55 crank-shaft. The oil is caught by these rings, and, dropping from their sharp edges, passes to the oil-bowl by means of channels v, Fig. 2.

The entire mechanism is inclosed by a casting made in convenient sections. The end 60 sections, Y, are secured at their upper ends and sides to the frame A by bolts, the lower ends being perforated to permit the passage of the crank-shaft, and are bolted to the base B of the interior casting. Where the crank- 65 shaft passes through the end sections the casting is bent or spun out beyond the lubricating

guard-rings X, as shown in Fig. 2, to afford a convenient construction for the reception of the rings X and the draining of the oil into the bowl. The upper parts of the end sections may be provided with shutters or lattice-work Y', the slats of which incline inward and upward to admit air to cool the engine while preventing the escape of the 70 splashing oil. Side sections, Y² Y³, of the 75 casing are made removable, so as to afford ready access to the engine for adjustment and repairs. As shown in Fig. 4, they are formed at their lower edges with flanges z, which interlock or overlap the edges of the bowl B'. 80 Their upper edges fit snugly against shoulders formed on the upper under edges of the cap-plate, and are held in position by turn-buttons Z, Fig. 1, or any other suitable device. This is a convenient structure and permits the sides 85 of the casing to be removed, and thus affords complete access to all parts of the engine. Of course the sides could be removably connected in a large variety of ways.

I am aware of British Patents No. 5,768 of 90 1882, and No. 680 of 1883, and do not claim the constructions of the engine-frames therein shown.

I claim as my invention—

1. The engine-frame constructed, substantially as described, with the bowl or trough shaped base, the standards or supports secured thereto, and the cap-plate secured to the standards.

2. The combination, substantially as set 100 forth, of the bowl-shaped base, the standards secured thereto, the cap-plate, and the removable sides or casing.

3. The combination, substantially as set 105 forth, of the base, the standards, the cap-plate, the steam-cylinder suspended from the cap-plate, the driving or crank shaft located between the suspended cylinder and the base, and the removable sides or casing.

4. The combination, substantially as set 110 forth, of the frame, an upright cylinder suspended from the top or cap-plate of the frame, the piston, the slide-head, and a guide in which the slide-head works, suspended from the cylinder.

5. The combination, substantially as set 115 forth, of a vertical steam-cylinder, piston, and piston-rod, the slide-head, and a longitudinally-slotted cylindrical guide in which the slide-head works, suspended from and supported only by the cylinder.

6. The combination, substantially as set 120 forth, of the supporting-frame, the cap-plate secured thereon, the steam-cylinder and valve-chest and their connecting-pipes secured to the cap, the slotted tubular guide secured to the end of the steam-cylinder and constituting an axial prolongation thereof, the slide-head secured to the piston-rod and sliding in the tubular guide, the connecting-rod, and the 130 crank-shaft.

7. The combination, substantially as set

forth, of the supporting-frame, its cap-plate, the steam-cylinder and valve-chest secured at one end to the under side of the cap-plate, the tubular guide secured to and constituting an 5 axial prolongation of the steam-cylinder, the slide-head connected with the piston-rod and sliding in the guide, the connecting-rod pivoted on the slide-head, the crank-shaft, the valve-piston, its connecting-rod, and its eccentric 10 on the crank-shaft.

8. The combination, substantially as set forth, of a frame, the flanged vertical depending cylinder, the piston-rod and slide-head, the flanged guide in which the slide-head 15 works, which guide is suspended from and supported by the cylinder, and the diaphragm or cylinder-head bolted between the cylinder and flanged guide.

9. The combination, substantially as set forth, of the cylindrical slotted guide, the slide-head, circular in cross-section and formed 20 with two depending lugs with curved outer

faces, which work in contact with the sides of the slotted guide, the piston, and the connecting-rod, which is connected with a cross-pin 25 carried by the two depending lugs.

10. The combination, substantially as set forth, of the frame and cap-plate, the suspended steam-cylinder, the valve-chest, the valve-piston, and the valve-cylinder having turned 30 or ground end edges or lips, α , for the purpose described.

11. The combination, substantially as set forth, of the frame and cap-plate, the depending cylinder, the upright valve-piston, and 35 counterbalancing devices, for the purpose described.

In testimony whereof I have hereunto subscribed my name.

NATHAN F. BURNHAM.
